CLAIM

(57) The ornamental design for a drain mat as shown and described.

DESCRIPTION

FIG. 1 is a top and front perspective view showing of a drain mat showing my new design;

FIG. 2 is a rear and bottom perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is an enlarged partial view of a portion indicated with numeric 9 in FIG. 1.

The dashed-dot-dashed broken lines in FIG. 1 and FIG. 9 are for the purpose of depicting the boundary lines of the enlarged view and form no part of the claimed design.
